CLAIM

The ornamental design for a hand-held diagnostic tool, as shown and described.

DESCRIPTION

FIG. 1 is a perspective view of the diagnostic tool;
FIG. 2 is a front elevational view of the diagnostic tool;
FIG. 3 is a rear elevational view of the diagnostic tool;
FIG. 4 is a top plan view of the diagnostic tool;
FIG. 5 is a bottom plan view of the diagnostic tool;
FIG. 6 is a left side elevational view of the diagnostic tool;
and,
FIG. 7 is a right side elevational view of the diagnostic tool.
The broken lines in the drawing depict portions of the hand-held diagnostic tool that form no part of the claimed invention.
